INVENTOR.

UNITED STATES PATENT OFFICE.

HARRY E. GIFFORD, OF BOSTON, MASSACHUSETTS, ASSIGNEE TO DOBSEY MANUFACTURING COMPANY, OF BOSTON, MASSACHUSETTS, A CORPORATION OF MASSACHUSETTS.

COVER.

1,108,108.

Specification of Letters Patent. Patented Aug. 18, 1914.

Application filed May 12, 1913. Serial No. 767,149.

To all whom it may concern:

Be it known that I, HARRY E. GIFFORD, a citizen of the United States, residing at Boston, in the county of Suffolk and State of Massachusetts, have invented new and useful Improvements in Covers, of which the following is a specification.

My invention relates to improvements in covers for milk bottles and the like, and the objects of my improvement are simplicity and economy in construction and providing means for 1, removing the paper seal from milk or other bottles; 2, protecting the entire mouth of bottle and contents from dust; 15 3, to provide means for engaging the neck of the bottle, and holding the cover in close contact therewith.

In the accompanying drawing: Figure 1 is a plan view of my improved cover, showing the shape when first struck from the sheet, also various shapes of spring fingers: Fig. 2 is a side view of the neck of a bottle in vertical cross section, a paper seal closing the mouth thereof, and the pointed or hooked end of a spring finger of the cover inserted in the seal for its removal; Fig. 3 is a side view of the neck of a bottle with cover in position thereon, the bottle being broken away to show the spring finger on the farther side: Fig. 4 is a cross section of the cover illustrating how a lining may be used in conjunction with the cover, as a part thereof or separate, for sealing or sanitary purposes.

Like numbers represent like parts in all the views, in which—

1 is the body of the cover which should be of sufficient size to completely cover the top or neck of bottle; 2, 3 and 4 are spring fingers which exert a pressure on the outside of the neck and hold the cover securely in place; 5 is the neck of a bottle; 6 is a paper seal; 7 is the lining of the cover.

In the manufacture of this cover I strike the same with a plurality of fingers from a sheet of suitable material as in Fig. 1, shaping one or more of the fingers to form a hook, two such forms being shown by fingers

3 and 4. I then bend the fingers at an angle with the cover and form the fingers similar as to an S shape, the inner surfaces of the lower bends being at a distance apart that will cause them to grip the neck of bottle when placed thereon. In some instances it is desirable to place on the under side of the cover a lining for sealing or sanitary purposes. The cover may also be turned down at the edge to conform to the shape of the bottle neck.

In operation I press the hooked end of one of the spring fingers through the paper seal and remove it from the neck of the bottle. I then press the cover down on the top of the bottle, the spring fingers passing over the swell of the neck, engaging the neck below, the form thereof causing the spring fingers to exert a downward pull upon the cover, effectually covering or sealing the bottle.

In the construction of my cover I require a plurality of spring fingers, but I do not confine myself to the form of hooked end thereof to the shapes shown herein; neither is it necessary that the edge of the cover shall be turned down, this varying according to the shape of the mouth of the bottle or vessel.

Having thus described my invention, what I claim as my invention is—

A sheet-metal blank stamped to provide a circular central body portion adapted to be directly mounted upon the exterior of the mouth of a bottle to close the same and carrying three equi-distantly spaced resilient clamping fingers integral therewith and depending therefrom to receive and hub the neck of the bottle, one integral finger having its free end pointed to be forced into the cap of the bottle to remove the same.

In testimony whereof I affix my signature in the presence of two witnesses.

HARRY E. GIFFORD.
